(57) **CLAIM**

The ornamental design for an enclosure for a container, as shown and described.

DESCRIPTION

FIG. 1 is a front elevational view of an enclosure for a container showing our new design with a lower container-receiving portion and an upper removable cap portion; FIG. 2 is a rear elevational view of the enclosure for a container of FIG. 1;

FIG. 3 is a right side elevational view of the enclosure for a container of FIG. 1, the left side elevational view being the mirror image of the right side elevational view;

FIG. 4 is a top plan view of the enclosure for a container of FIG. 1;

FIG. 5 is a bottom plan view of the enclosure for a container of FIG. 1;

FIG. 6 is a perspective view taken from the bottom and front side of the enclosure for a container of FIG. 1; and,

FIG. 7 is a perspective view taken from the bottom and rear side of the enclosure for a container of FIG. 1.
